Samuel Paynor, of New York, New York
Letters Patent No. 2340 dated June 26, 1866
Design for an Envelope

The Schedule referred to in the Letters Patent and making part of the same.

To all whom it may concern

It is known that I, Samuel C. Paynor, of the City, County, and State of New York, have invented a new and useful Design for Envelopes, and I do hereby declare that the following is a full, clear, and exact description thereof, which will enable others skilled in the art to understand the same, reference being had to the accompanyed drawing forming part of this Specification.

The drawing is a back view of this invention.

This invention relates to a new and ornamental design for what is known as "Open end envelope" whereby side envelope attains a novel and elegant appearance which distinguishes the same from all envelopes heretofore invented and known to me.

A. A. represents the end flaps, which extend from the corners, a with inclined lines to the curved edges, C. The ends of these flaps are rounded off and when the flaps are turned down they strike the seam, D, of the side flaps B. B. said seam being made to extend in a longitudinal direction through the middle of the envelope.

Having thus described my invention, what I claim as new and desire to secure by Letters Patent is the design for an Envelope as shown and described.

The above specification of my invention signed by me this twenty-sixth day of April 1866.

Samuel Paynor
